(57) **CLAIM**

The ornamental design for a safety razor handle, as shown and described.

DESCRIPTION

FIG. 1 is a bottom perspective view of a safety razor handle; FIG. 2 is a top perspective view thereof; FIG. 3 is a bottom view thereof.

FIG. 4 is a top view thereof.

FIG. 5 is a front view thereof.

FIG. 6 is a rear view thereof.

FIG. 7 is a side view thereof; and,

FIG. 8 is a side view thereof, opposite the side shown in FIG. 7.

The broken lines in the figures are for the purpose of illustrating portions of the safety razor handle and form no part of the claimed design
